[57] CLAIM

The ornamental design for a wall mountable modular support panel, as shown and described.

DESCRIPTION

FIG. 1 is a top, front, and right side perspective view of a wall-mountable modular support panel showing my new design;

FIG. 2 is a right side elevational view thereof, the left side being a mirror image of that shown;

FIG. 3 is a top plan view thereof, the bottom being a mirror image of that shown; and

FIG. 4 is a rear elevational view thereof.

Fig. 2.

Fig. 1.
